Primary Examiner—Melody N. Brown*Attorney, Agent, or Firm*—Townsend and Townsend and Crew[57] **CLAIM**

The ornamental design for a bicycle porter, as shown and described.

DESCRIPTION

FIG. 1 is a perspective view of a bicycle porter showing my new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a front elevational view thereof;

FIG. 7 is a rear elevational view thereof;

FIG. 8 is a perspective view of a second embodiment of a bicycle porter; and,

FIG. 9 is a perspective view of a third embodiment of a bicycle porter.

The bottom, rear and left side views of the second and third embodiment of the bicycle porter are substantially similar in appearance to the first embodiment of the bicycle porter.
